[57] CLAIM

We claim the ornamental design for an electrical alternator, as shown and described.

DESCRIPTION

FIG. 1 is a perspective view showing our new design for an electrical alternator;

FIG. 2 is a rear view thereof;

FIG. 3 is a front view thereof;

FIG. 4 is a top view thereof;

FIG. 5 is a right side view thereof;

FIG. 6 is a bottom view thereof; and,

FIG. 7 is a left side view of thereof when the alternator of FIGS. 1–6 is rotated by 180 degrees.

The broken-line disclosure in the views is for illustrative purposes only and forms no part of the claimed design.
